METHOD OF PRODUCING TOWLINE PLUGS

Aurel Vaszin, Dayton, Ohio

Application May 10, 1944, Serial No. 534,956

2 Claims. (Cl. 29—148)

This invention relates to a method of producing a release plug and more particularly to the method of manufacturing a release plug adapted for use in tow lines for towing gliders, targets and the like by airplanes.

An object of this invention is to provide a method of producing a tow line plug from a forging wherein the tow line plug has a pair of eyes or loops joined by a plate member having at least one face thereof conically shaped and provided with finished marginal portions adapted to engage a release cylinder.

Another object of this invention is to provide a method for economically producing a tow line plug that is simple in construction yet dependable and efficient.

Other objects and advantages reside in the construction of parts, the combination thereof and the mode of operation, as will become more apparent from the following description.

Referring to the drawing, Figure 1 is a top plan view of a forging from which the plug is made before the forging has been finished.

Figure 2 is an end elevational view of the forging shown in Figure 1.

Figure 3 is a side elevational view of the forging shown in Figure 1.

Figure 4 is a top plan view of the plug after the forging shown in Figure 1 has been turned and finished.

Figure 5 is an end view of the plug shown in Figure 4.

Figure 6 is a side elevational view of the plug shown in Figure 4.

Figures 4, 5 and 6 have been drawn to a smaller scale than Figures 1, 2 and 3.

In towing gliders and the like by airplanes, the tow line is fixedly attached to a reel mounted in the airplane. The extreme end of the tow line is formed into a loop and engages a thimble like the one disclosed in my co-pending application Serial No. 533,607 filed May 1, 1944, for Tow line thimble.

A piston, not shown, is mounted on the glider. In this piston is located a releasably mounted plug, which plug is attached to the clevis integral with the thimble. The plug piece is forged from a bar of steel.

The forged plug is shown in Figures 1 to 3 inclusive and includes a disc-like portion 10 merging into a loop portion 12 on one side and a retaining loop portion 14 on the opposite side of the disc-like portion 10. The sides of the forged disc-like portion 10 taper, so as to provide conical portions 16 and 18. The loop portion 12

is substantially circular in cross sectional area. The retaining loop portion 14 has a substantially circular cross sectional area throughout the greater portion of the periphery. A pair of retaining member facets 20 form a dihedral angle of approximately 140° with respect to each other. These facets are engaged by the retaining means mounted in the cylinder not disclosed herein, as the retaining means does not form a part of this invention. The piece shown in Figures 1 to 3 inclusive is preferably formed by die forging and is integral and homogeneous throughout.

Due to the fact that the disc-like portion 10 must be snugly seated in the end of the retaining cylinder, it is necessary to finish the surface of the disc-like portion throughout its entire margin. As may best be seen by referring to Figures 4, 5 and 6, the margin 22 has been turned so as to be cylindrical. The face 24 has been turned, so has the face 26. In addition to turning the face 24, the central portion 28 has also been turned so as to have a flat area throughout the entire side with the exception of the island portions 30 and 32 surrounding the ends of the loop portion 14. This turning operation may be accomplished by machining so as to remove the metal leaving a substantially flat surface under the loop portion 14. These island portions 30 and 32 help to center the plug in the cylinder, in that the island portions 30 and 32 are bounded by arcuate margins. The convex margins of the island portions provide seats for the cylinder. The concave margins are the result of the tooling operation. In addition thereto, these island portions provide reinforcements, reenforcing the disc-like portions 10 in the vicinity of the legs of the retaining loop portion 14. The face 26 of the disc-like portion 10 terminates in a conical portion 34 that extends throughout the center of the disc and gives the disc rigidity.

The plug disclosed herein is easily produced by forging and easily machined, resulting in a strong, homogeneous plug without the use of welding and without the use of a plurality of parts. The forging, after it has been machined, may be either annealed or tempered or otherwise heat-treated, so as to have the proper hardness. For the purpose of preservation, the finished article may be cadmium plated, zinc plated or otherwise coated.

Although the preferred embodiment of the device has been described, it will be understood that within the purview of this invention various changes may be made in the form, details, pro-

portion and arrangement of parts, the combination thereof and mode of operation, which generally stated consist in a device capable of carrying out the objects set forth, as disclosed and defined in the appended claims.

Having thus described my invention, I claim:

1. The process of producing a tow line plug adapted to engage a retaining cylinder provided with releasing means, the process including the steps of forging from bar stock a disc-like portion provided with a pair of oppositely disposed loops one of which is provided with internal facets, turning the periphery of the disc-like portion so as to provide a cylindrical surface, turning the margin of one side of the disc-like portion leaving a conical portion in the center thereof, and machining the opposite side of the disc-like portion by removal of metal leaving a pair of islands integral with the legs of the loop extending from

said side, the islands being provided with cylinder-engaging convex surfaces.

2. The process of producing a tow line plug adapted to engage a retaining cylinder provided with releasing means, the process including the steps of forging from bar stock a disc-like portion provided with a pair of oppositely disposed loops, forging a pair of facets on one of the loops forming a dihedral angle of 140°, turning the periphery of the disc-like portion so as to provide a cylindrical surface, turning the margin of one side of the disc-like portion, leaving a conical portion in the center thereof, and machining the opposite side of the disc-like portion by removal of metal leaving a pair of islands integral with the legs of the loop extending from said side, the islands being provided with cylinder-engaging convex surfaces.

AUREL VASZIN.
